United States Patent Office

Des. 224,682

Patented Aug. 29, 1972

224,682

DATA PROCESSOR

Loring C. Bixler, Vestal, Arnold M. Davis, Poughkeepsie,
Donald F. Lahey, Vestal, Walter S. McCormick, Jr.,
Poughkeepsie, and Edward R. Wiener, Vestal, N.Y.,
assignors to International Business Machines Corpora-
tion, Armonk, N.Y.

Filed Dec. 21, 1970, Ser. No. 26,610

Term of patent 14 years

Int. Cl. D14—02

U.S. Cl. D26—5

FIG. 1

FIG. 2

FIG. 3

FIG. 4

FIG. 5

FIG. 6

FIG. 1 is a front perspective view of a data processor showing our new design;

FIG. 2 is a front elevational view thereof;

FIG. 3 is a rear elevational view thereof;

FIG. 4 is a right side elevational view thereof;

FIG. 5 is a left side elevational view thereof; and

FIG. 6 is a top plan view thereof.

We claim:

The ornamental design for a data processor, as shown and described.
